CLAIM

The ornamental design for a combined cabinet holder for paper rolls and perpetual calendar, as shown.

DESCRIPTION

FIG. 1 is a front perspective view of a combined cabinet holder for paper rolls and perpetual calendar showing my new design;

FIG. 2 is a front elevational view thereof;

FIG. 3 is a right side elevational view thereof;

FIG. 4 is a top plan view thereof; and

FIG. 5 is a bottom plan view thereof.

FIG. 1.FIG. 2.FIG. 3.FIG. 4.FIG. 5.
